UNITED STATES PATENT OFFICE.

PATRICK H. COSTELLO, OF BOSTON, MASSACHUSETTS.

FIRE-ESCAPE.

SPECIFICATION forming part of Letters Patent No. 257,663, dated May 9, 1882.

Application filed March 6, 1882. (No model.)

To all whom it may concern:

Be it known that I, PATRICK H. COSTELLO, of Boston, in the county of Suffolk, of the State of Massachusetts, have invented a new and useful Improvement in Fire-Escapes; and I do hereby declare the same to be described in the following specification and represented in the accompanying drawings, of which—

Figure 1 is a front view, and Fig. 2 a side view, of the upper part of a building with my fire-escape applied thereto. Fig. 3 is a front elevation, Fig. 4 an end view, and Fig. 5 a longitudinal section, of the ladder and its coiling and supporting mechanism, the three last figures being on an enlarged scale in comparison to that of the first and second.

The nature of my invention is defined in the claims hereinafter presented.

In carrying out my said invention I fix to the building A, to project beyond the upper part of its front in manner as represented, a strong rail, B, which may also extend from said front around one or both sides and the rear of the building. The said rail is to support the ladder-case or carriage C, which is furnished with a hooked standard, a, carrying a wheel, b, to bear on the upper edge of the rail. Two guides, C C, project upward from the case, they being arranged with the hooked standard a in manner as shown. The case is cylindrical, and has within it, concentrically, a shaft, d, duly supported, so that it can be revolved by a crank, e, fixed to it, or by means of a sprocket-wheel and an endless chain applied to the latter. There are fastened on the shaft and within the case two disks or heads, f f, and between them there is attached to the

shaft one extremity of a rope ladder, D, the case being provided with an opening, o, in its lower part, for the ladder to pass from or to be drawn up within it. A rope, E, fixed to the said ladder and depending from it, serves as a means to enable a person to draw it downward out of the case.

From the above it will be seen that this ladder, with its case, can be moved along on the supporting-rail, so as to cause the ladder to come in front of any window of the building. In case of the building being on fire a party or fireman on the ground can with a hook reach the depending line, and by pulling on it draw down the ladder, and by means of it move it along in front of any window or windows from which any of the inmates may be desirous of escaping. The guides c c, by bearing against the front of the rail, serve to keep the wheel from running off it, and they allow the wheel to turn a corner, where the rail bends or turns around such, of the building.

I claim as my invention—

1. The ladder-case provided with the ladder, its coiling-shaft, and the central standard and its wheel, and the guides, arranged substantially as set forth.
2. The guide-rail arranged with the building, as described, in combination with the coiling-ladder, and with its case and coiling-shaft, and with the sustaining-standard and its wheel and guides, arranged with such case, as shown and described.

PATRICK H. COSTELLO.
